UNITED STATES PATENT OFFICE.

WILLIAM CARR LOCKWOOD, OF SHEFFIELD, ENGLAND.

STEAM-BOILER.

SPECIFICATION forming part of Letters Patent No. 728,591, dated May 19, 1903.

Application filed June 28, 1902. Serial No. 113,661. (No model.)

To all whom it may concern:

Be it known that I, WILLIAM CARR LOCKWOOD, a subject of the King of Great Britain and Ireland, and a resident of Sheffield, England, have invented certain new and useful Improvements in Steam-Boilers, (for which I have filed an application for British patent, No. 8,187, dated April 8, 1902;) and I do hereby declare the following to be a full, clear, and exact description of the same.

This invention relates to a combined water-tube boiler, and is hereinafter described with reference to the accompanying drawings and characterized in the claims.

On the drawings, Figure 1 represents a front elevation; Fig. 2, a sectional elevation; Fig. 3, a sectional side elevation; and Fig. 4, a plan, partly in section.

In the improved boiler a cross-tube-fitted water-jacketed fire-box is surrounded at its sides and back end by a flue-chamber and vertical-tube auxiliary water-heaters, of which the water-space is in communication respectively at the bottom and top with the water-space of the fire-box jacket, and the flue-space is in communication with the fire-box interior through tubes crossing the fire-box jacket and with an exit-flue leading to the chimney, the water-spaces of the fire-box jacket and of the surrounding auxiliary water-heaters being, respectively, in communication at their upper parts and also with steam-ducts leading to a steam-receiver common to the series.

The fire-box *a*, fitted with longitudinally arranged fire-bars, (not shown,) is jacketed by a casing *b*, inclosing a water-space *d* and a steam-space *f*, and is crossed by diagonal water-tubes *g*, which connect different elevations of the water-space and aid in heating and circulating the water therein. The water-space is also crossed at its sides and back end by flue-tubes *h*, which lead from different parts of the fire-box through such water-space to different parts of a flue-chamber *i*. The chamber *i* surrounds the sides and back end of the jacketed fire-box and also the vertical tubes of the auxiliary water-heaters. At its lower part it is fitted with a water-chamber *k*, which communicates by pipes *l* with the water-space *d*, and at its upper part it is fitted with a water-chamber *m*, which communicates by pipes *n* with the water and steam space above the

crown of the fire-box. The chambers *k m* are connected by vertical tubes *o*, which traverse the depth of the flue-chamber and are expanded into flanged plates *p*, which are bolted to flanges of the chambers *k m*, so as to allow the plates and tubes to be together removed from the chambers. The flue-chamber *i* communicates by smoke-holes *u* with a surrounding flue *q*, which leads to a chimney. (Not shown.) The steam-spaces *f r* of the chambers *d m* also respectively communicate by pipes *s* with a steam-receiver *t*, common to the whole and which is provided with an end manhole, safety-valves, pressure-gages, and the customary paraphernalia of such apparatus. Thus in the improved combined water-tube boiler the furnace-gases successively circulate in the fire-box, pass through the surrounding water-jacket, and circulate in the surrounding flue-chamber and among the vertical water-tubes therein before escaping to the chimney, while the feed-water, which is supplied to the chamber *k* by a pipe *c*, circulates upwardly mainly through the auxiliary water-heater pipes and partly to the fire-box jacket, its efficient circulation through both such means of heating it being insured by the relative arrangement and connections of such parts.

What I claim is—

1. A water-tube boiler comprising the combination of a water-jacketed fire-box consisting of inner and outer casings inclosing between them a water-space, diagonal water-tubes crossing the fire-box and connecting different elevations of the water-space, flue-tubes leading laterally from the fire-box through the water-space, a flue-chamber surrounding the water-jacketed fire-box at its sides and back and communicating with the fire-box through said flue-tubes, a flue surrounding said flue-chamber and communicating with a chimney, auxiliary water-heaters consisting of separate chambers respectively communicating with the bottom and top of the fire-box water-jacket and of connecting-tubes vertically passing through the flue-chamber, steam-ducts leading from the steam-spaces of the fire-box jacket and of the auxiliary water-heaters, and a steam-receiver communicating with and common to all said steam-ducts, as set forth.

2. In a steam-generator, in combination, a vertical fire-box of a long narrow formation having flat sides placed relatively near together, a plurality of crossing diagonal water-tubes leading alternately from its opposite sides to opposite sides of its crown, a vertical water-jacket of a long narrow formation with flat sides inclosing the fire-box at its sides and crown, a plurality of flue-tubes connecting the shells of the fire-box and water-jacket at a plurality of levels and adapted to lead the furnace-gases through the side and back parts of the water-jacket to the exterior of the latter, a continuous water-trough made in sectional lengths arranged around the sides and back of the water-jacket at the bottom level of the latter, a plurality of water-tubes connecting the water-jacket and said trough at intervals and adapted to insure circulation of the water at such level, a bed-plate adapted to support such water-trough, an upper chamber substantially duplicate in form to that of said trough made in sectional lengths arranged around the sides and back of the water-jacket at the top level of the latter in inverted opposite relation to the trough, a plurality of vertical water-tubes arranged in a plurality of rows set in top and bottom tube-plates and adapted to connect said trough and opposite chamber at the sides and back of the

water-jacket so as to inclose and connect the interiors of such trough and chamber while leaving flue-spaces between themselves, a plurality of water and steam tubes connecting said chamber with the upper water and steam space of the water-jacket, a steam-receiver surmounting the water-jacket, a plurality of steam-pipes connecting the steam-spaces of the water-jacket and said chamber at intervals with the steam - receiver by junctions common to both connections, a casing surrounding said side and back sections of vertical water-tubes so as to form a flue bounded at the bottom and top by said trough and opposite chamber and at the inner sides and back by the water - jacket and adapted to cause the furnace-gases to circulate horizontally around the same and among the vertical tubes and having flue-holes in its outer sides, and a flue surrounding such casing at its front, sides and back at the level of its flue-holes and adapted to lead the exhausted furnace-gases to a chimney.

In testimony whereof I have signed this specification in the presence of two subscribing witnesses.

WILLIAM CARR LOCKWOOD.
